UNITED STATES PATENT OFFICE.

CLARENCE C. TODD, OF BEAUMONT, TEXAS.

VAPOR-BURNER.

SPECIFICATION forming part of Letters Patent No. 794,263, dated July 11, 1905.

Application filed April 28, 1905. Serial No. 257,839.

To all whom it may concern:

Be it known that I, CLARENCE C. TODD, a citizen of the United States, residing at Beaumont, county of Jefferson, State of Texas, have invented a new and useful Improvement 5 in Vapor-Burners, of which the following is a specification.

The main object of the invention is to provide for efficient combustion of oil or fluid combustible, particularly in stoves and fire-boxes, and relates to improvements on those vapor-burners in which the jet of combustible or vapor is directed downward into the fire-box or fire-pot from the outside thereof, thereby securing the conditions for perfect combustion and for diffusion of the heat throughout the fire-chamber or stove, preventing corrosion of the burner-head and avoiding soot and fumes.

Another object of the invention is to provide a burner wherein the burner-head or jet-piece is outside of the fire-chamber or fire-box, thereby obviating the danger of overheating and clogging of the outlet and keeping same in plain view for inspection.

Another object of the invention is to provide a burner that can be applied to a stove with a minimum of trouble and expense and that requires no drilling of holes or fittings except a single clamp.

The invention is particularly intended for application to ordinary stoves with removable lids, and an important object of the invention is to provide a burner which can be set in or on the stove in place of one of said lids, which space is not lost, as any cooking vessel can be set on said burner.

The accompanying drawings illustrate the invention.

Figure 1 is the perspective of the stove provided with the burner; Fig. 2, a perspective of the burner; Fig. 3, a vertical section thereof. Fig. 4 is a detail section of the fastener for a burner.

Referring to Fig. 1, 1 designates an ordinary cook-stove, having the ordinary lids 2 occupying the holes 3 in the top 3, and air-admitting slides or dampers 4 at its front. 5 represents a plate which takes the place of

one of the stove-lids and carries the burner 5° parts which are attached thereto.

The burner comprises a vapor-generator or vaporizing chamber or member 6, an inlet-pipe 7, and an outlet-pipe 8, pipes 7 and 8 being secured to plate 5 and to the vaporizing- 55 chamber 6 to support the latter from plate 5. The outlet-pipe 8 is provided with a jet-piece or burner-head 9, which extends laterally therefrom, the vapor-outlet 10 in said burner-head being directed downward, preferably in 60 a substantially vertical direction. Directly below said outlet the lid or plate 5 has an opening or perforation 12, through which the vapor or combustible is projected from the burner-outlet into the fire box or space below 65 the cover-plate 5. Vaporizing-chamber 6 is preferably directly below the burner-outlet, so as to be in the line or path of the jet or flame issuing therefrom.

The burner-head 9 may comprise a cap 9' 70 on the end of a nipple 13, screwed into an elbow 14 at the top of the pipe 8, which extends vertically downward through plate 5 and is secured to plate 5 by screwing into the same. The inlet-pipe 7 is similarly secured by screw- 75

The generator or vaporizing chamber 6 may consist of two sections of pipe 6' placed parallel to each other and screwing at their ends in U-fittings 17, the pipes 7 and 8 being tapped 80 into the tops of the respective fittings 17. A base or extension is provided on the vaporizing-chamber, the same consisting of a plate or casting 18, having a flange 19 extending upward around the parts 6' 17 to form a starting-pan or oil-cup in which the generator sits, forming a chamber for generation of the gas in starting. The member 18 is secured to member 6 by a clamp consisting of bolts 20, engaging with the said plate or casting and 90 with spreader 21, extending over the top of the pipes 6'. Said spreader has an enlargement or disk portion 21', which serves as a spreader to receive the direct impingement of the vapor jet or flame and communicate the 95 heat to the generator. 21 is an annular rib on the spreader 21', having radial channels 21'', connecting with or leading to radial chan-

nels 21''' in the edge of the enlargement or disk portion 21' for conducting the oil for initial heating over the edge of the spreader 21 and onto the U-fittings 17. Said plate or casting 18 has a flange portion 22 extending laterally therefrom in a horizontal direction to increase the area of the metal exposed to the flame and acting both as a deflector for the flame and as a means for absorbing heat from the flame for heating the vaporizing-chamber.

23 designates a clamp-plate secured by screw 23' to the plate 5 between lugs 23" and engaging with the stove-top to hold the burner in place. Plate 5 rests on top of the stove and is sufficiently large to cover the largest hole in an ordinary stove and will therefore overlap the hole if it is a small one.

The inlet-pipe 7 has screwed at its upper end an elbow 24, from which a pipe 25 leads 20 to a valve 26, preferably a needle-valve. The oil-supply pipe 27 for said valve may extend alongside the stove and be fastened thereto by a suitable clamp (indicated at 28) and extending upwardly into an oil-tank 29, the outlet 25 of said oil-tank being provided with valve 30.

In applying the device to an ordinary stove it is only necessary to place the supporting-plate 5 in one of the holes in the stove-top and fasten the device to the stove by means of 30 the clamp 28, no boring or fitting work being necessary.

In operation the valves 30 and 25 are opened, allowing oil to pass through the generator or vaporizing member and allowing a little oil to 35 run down onto the spreader 21' and over the generator in the oil-cups for this flange 18. This oil being ignited, the flame heats the oil in the generator so as to generate vapor, and the vapor so generated issues from outlet 10, 40 and passing down through the opening 5 is admixed therein to a certain extent with air, which makes a gas-vapor that burns within the fire-box. The flame spreads out within the fire-box under the stove-top. The amount 45 of air-supply can be regulated by opening the front dampers, so as to produce perfect combustion. The quantity of vapor can be regulated by the needle-valve 26, so as to make a

large flame or a small flame. The construction of the burner is such that the flame can 50 be turned down to a very small jet, just enough to keep it alight, and the generator will still keep the burner in operation.

It will be seen that the space on the stove occupied by the burner is not wasted, as any 55 cooking vessel can be placed thereon, lugs 31 being provided to support the same.

What I claim is—

1. A vapor-burner comprising a supporting-plate having an opening, a generator, an 6c inlet-pipe, an outlet-pipe having an outlet directed downward over the plate-opening, a cup-plate located beneath the generator, having a flange surrounding the latter, a spreader 65 surmounting the generator and bolts whereby the cup-plate and spreader are clamped to the generator.

2. A vapor-burner comprising a supporting-plate having an opening, a generator consisting of U-fittings and two pipe-sections 70 connecting the fittings, an inlet-pipe, an outlet-pipe having an outlet directed downward over the plate-opening, a cup-plate, located beneath the generator, having a flange surrounding the latter, a spreader 75 surmounting the generator and bolts whereby the cup-plate and spreader are clamped to the generator.

3. A vapor-burner comprising a supporting-plate having an opening, a generator, an inlet-pipe, an outlet-pipe having an outlet directed downward over the plate-opening, a cup-plate, located beneath the generator, having a flange surrounding the latter, a spreader 80 surmounting the generator and having an enlargement formed with radial channels at its 85 edges, and an annular rib having radial channels connecting with the radial channels of the enlargement, and bolts whereby the cup-plate and spreader are clamped to the generator.

In testimony whereof I have hereunto set 90 my hand, at Los Angeles, California, this 20th day of April, 1905.

CLARENCE C. TODD.

In presence of—

JAMES R. TOWNSEND,
JULIA TOWNSEND.
